UNITED STATES PATENT OFFICE.

LANSING ONDERDONK, OF NEW YORK, N. Y., ASSIGNOR TO UNION SPECIAL MACHINE COMPANY, OF CHICAGO, ILLINOIS, A CORPORATION OF ILLINOIS.

MULTIPLE-NEEDLE CHAIN-STITCH MACHINE.

1,123,576.

Specification of Letters Patent.

Patented Jan. 5, 1915.

Application filed August 29, 1904. Serial No. 222,613.

To all whom it may concern:

Be it known that I, LANSING ONDERDONK, a citizen of the United States, residing at New York, in the county of New York, 5 State of New York, have invented certain new and useful Improvements in Multiple-Needle Chain-Stitch Machines, of which the following is a description, reference being had to the accompanying drawing and to 10 the letters and figures of reference marked thereon.

My invention relates to chain stitch sewing machines, and more particularly to multiple needle chain stitch machines, although 15 several of my improvements are equally adapted to a single needle machine.

An object of the invention is to provide a looper operating mechanism, wherein the looper may be given variable movements, 20 which looper operating mechanism is so constructed that the looper may be readily moved to a position where the same may be easily threaded.

A further object of the invention is to 25 provide a looper operating mechanism, wherein the looper is positively moved back and forth and given a dwell at certain times, which looper operating mechanism is of simple construction.

30 A further object of the invention is to provide means coöoperating with the loopers to aid in positioning the loop for the entrance of the needle.

These and other objects will in part be obvious and will in part be hereinafter more 35 fully disclosed.

In the drawings, Figure 1 is a side elevation of a sewing machine, showing my invention, the bed plate being removed; Fig. 40 2 is an end elevation of the same; Fig. 2^a is an enlarged view similar to that shown in Fig. 2, but with the parts in different relation to each other; Fig. 3 is a horizontal section taken on the line 3—3 of Fig. 1; Fig. 4 is a detail perspective view of the 45 front end of the machine; showing the bed plate removed and the loopers in threading position; Fig. 5 is a perspective view of the looper-oscillating mechanism, the parts being separated to more clearly show the construction; Fig. 6 is a detail sectional view 50 showing in side elevation the thread controller; Fig. 7 is a detail view of the feed-operating mechanism; Figs. 8 and 9 are de-

tail sections, showing a non-thread-carrying 55 looper and needle in different stitch-forming positions; Fig. 10 is an under plan view of the throat plate; Figs. 11 and 12 show in top and side elevation, the spreader plate; Fig. 13 is a detail, showing the coöperation 60 of the needle, the threaded looper and the spreader which engages the looper thread; Fig. 14 is a detail, showing the looper in side elevation and the supporting shaft in section. 65

The machine shown in the drawings is in the main of the usual type of the chain stitch sewing machines, and consists of the overhanging arm or gooseneck I, carrying lugs at the forward end in which the needle 70 bar J reciprocates. Said needle bar is actuated by the lever K, fulcrumed at K' on the overhanging arm, and connected to the needle bar by a link K². The opposite end of the needle lever is connected to the link 75 K³, which is operated by the usual eccentric on the driving shaft. The needle bar is provided with a plurality of needles N, and suitable thread guides coöperate therewith in supplying thread to said needles. 80

All of the above parts are of the usual construction, and will not be further described in detail.

The main shaft O extends beneath the bed plate, and is carried in suitable bearings. 85 Parallel with the main shaft O is the looper shaft P, which is carried in suitable bearings which permit said shaft to oscillate and to move endwise. Screw-threaded on the inner end of the looper shaft is a sleeve P', 90 which has its end contracted at P², to receive and partially inclose the ball or enlarged end P³ of a link P⁵. This link P⁵ is connected to a bell crank lever P⁶, pivoted at P⁷ to the bed plate. The opposite end of the bell crank lever P⁶ is connected to a link P⁷, which in turn is connected to and actuated by a ball eccentric on the main shaft O. The bell crank lever is slotted at P⁹, and is connected to the link P⁷ by a bolt P¹⁰. This 95 affords an adjustment whereby the throw of the bell crank may be varied. The ball connection between the link P⁵ and the looper shaft allows the shaft to oscillate, and through this connection the looper shaft is 100 given an endwise movement. 105

The looper shaft is oscillated by the following mechanism: The main shaft O ex-

tends through the forward housing of the bed plate, and carries on the end thereof a crank arm E', which is provided with a crank pin E. Pivoted to the bed plate at A, 5 is a rock lever B, which carries a stud C connected to the crank pin E by a link D'. The upper end of the rock lever B is curved backwardly at B', and provided with an opening to receive the screw stud B². The looper shaft P extends through the housing 10 at the forward end of the machine, and has loosely mounted thereon a crank frame G. Said crank frame is perforated to receive the screw stud G'. A link F connects the studs B² and G', and communicates the movements of the rock lever B to the crank frame G. The crank frame G extends to the opposite side of the looper shaft P, and has a portion of 15 said end cut away. On this end of the crank frame and in said cut away portion is a stud G². On said stud is a sleeve H, carrying a latch piece H', and a pin H². On the extreme outer end of the looper shaft P, is a 20 turning block G³. This block is split from its central perforation outward and carries a set screw G⁷, by means of which the turning block is rigidly secured to the looper shaft. The turning block has a projecting 25 shoulder which is curved at G⁸, to correspond to the curvature of the head of the link F. Said block G³, also has a stop G⁹, to limit the movement of the block, relative to the crank frame G, and a square shoulder 30 G¹⁰ at its opposite end underneath which the latch piece H' engages and normally holds the stop G⁹ in engagement with the crank frame G. A suitable spring R is connected to the pin H²; and to the stud G', and 35 tends to hold the latch beneath the turning block. It will be apparent that when the latch is beneath the turning block, that then 40 said block will partake of the movement of the crank frame G, and said movements will be communicated to the looper shaft. On the other hand, when said latch is drawn outward from beneath the turning block, then 45 the turning block is free to turn independently of said crank frame. The object of 50 releasing the looper shaft from its operating mechanism is to enable the operator to turn the loopers into convenient threading position. Where a plurality of thread-carrying loopers are used a great deal of 55 difficulty has been experienced in threading the same. In my present machine, the forward portion of the bed plate Q is divided and hinged at Q'. In threading my loopers, this portion of the bed plate is lowered, the 60 latch H' released from under the turning block, and said block turned by hand to move the loopers forward from beneath the feed plate and feed dog, as shown in Fig. 4. In this position the loopers can be easily 65 threaded, and then returned to operative

position, the latch springing to place and locking the parts in position for operation. By loosening the set screw G⁷, the position of the looper shaft may be adjusted.

The thread-carrying looper, as shown in Fig. 13, consists of a shank portion V², having an open sided bearing V, to engage the looper shaft P, and is held in place on said shaft by a set screw V'. By this construction of open sided bearing, the loopers may be assembled or removed from the looper shaft without removing the shaft or other parts. This is found to be very convenient in multiple needle machines, where it is often desired to change the number of needles and loopers. Supported in the shank portion in the usual manner, is the looper L. This looper L has the usual thread eyes to receive the looper thread.

In Figs. 8 and 9, I have shown a non-thread carrying looper. Said looper has the thread notch L² and shoulder L³ to properly manipulate the needle thread.

In connection with my looper mechanism, I use a spreader S, shown in detail in Figs. 10, 11 and 12. This spreader consists of a bar having slotted ends S' in which screws S² engage to adjustably secure said spreader bar to the bed plate. The spreader bar is provided with projecting fingers, which lie adjacent to the needle slots, and co-operate with the looper and needle in forming the stitches in a manner hereinafter described.

The thread for the loopers leads through suitable tensions and guide eyes to the stationary guide eyes W and W', thence through the eyes W² to the loopers. The guide eyes W, W', are carried by a bracket W³, slotted at its lower end as at W⁴, and is adjustably connected to the bed plate by the screw W⁵.

The controller or take-up for the looper thread consists of a lever T, shown in Fig. 6, pivoted to a supporting link T', in turn pivoted to a lug T² on the bed plate. Intermediate its ends the lever T surrounds an eccentric T³, which gives the free end of said lever an up and down movement. On the free end of said controller lever or take-up is secured a guide piece T⁴, having eyes T⁵. The thread passes through the eyes T⁵, after leaving the eyes W and before entering the eyes W'.

The movements of the controller or take-up are as follows: The take-up begins to move upwardly while the loopers are moving forward and reaches its extreme upward position between the stationary guide eyes at about the time the loopers begin their needle-avoiding movement, the take-up then moves gradually downward while the loopers are moving to the side and to the rear. The upward movement of the take-up draws up the looper thread from the previous stitch.

In Fig. 7, I have shown the feed rock shaft Y, which is operated by a link Y' connected to and actuated by an eccentric on the main shaft. These parts are of the usual construction, and it will not be necessary to give further description of the same.

The operation of the looper mechanism is as follows: Assuming the parts in the position shown in Fig. 2^a, the looper will be in its extreme backward position, and about to enter the needle loop. As the crank pin E on the end of the main shaft rotates, it causes the rock lever B, through its connecting link D to move backward, and this movement of the rock lever is communicated through the link F and crank frame G to the looper shaft. The movement of the looper forward will increase rapidly to a maximum owing to the toggle effect of the link F and rock lever B. Soon after the crank pin passes through 90° of movement from the position shown in Fig. 2^a, the arc of movement of said pin approximates the arc of movement which would be described by the link D' moving on the stud C, as a fulcrum. At the same time the toggle connections F and B reach an ineffective position, the result of which is that the looper 30 stops and has a considerable dwell. The looper begins to move backward after the parts reach the position shown in Fig. 2, and when the crank pin approaches the position shown in Fig. 2^a, the looper has 35 reached its rear position, and, owing to the crank pins passing the dead center, the looper again dwells. By this arrangement of mechanism, I am able to use a short looper, which is given a rapid forward and backward movement with long periods of dwell at each end of its stroke. During the dwell in the movement of the looper, said looper is moved sidewise to give the same the needle-avoiding movement. In this 40 needle-avoiding movement, the loop is engaged by the spreader and opened. When a thread-carrying looper is used, (see Fig. 13), the spreader finger projects into the path of the strand of the looper thread leading to the previous stitch and engages the same as the looper moves sidewise, thus opening the loop for the needle. When a single chain stitch is being made by a non-thread-carrying looper, the needle loop, 45 (see Figs. 8 and 9), is held well forward by the shoulder L², so that the strand leading to the previous stitch is engaged by said spreader finger, and thus the loop is opened to receive the needles.

50 While I have described in detail the preferred form of my invention, it is obvious that many changes may be made therein by those skilled in the art, to which it appertains, without departing from the spirit of 55 my invention.

Having thus described my invention, what I claim as new and desire to secure by Letters Patent, is:—

1. A sewing machine, including in combination a work support, a driving shaft, a threaded looper, operative connections between the driving shaft and the looper, said work support having a vertical portion covering the looper, and means whereby said vertical portion may be moved to give access to the looper, said operative connections between the looper and driving shaft including a latch for holding the looper connected to the driving shaft, whereby upon releasing the latch said looper may be disconnected from the operating shaft and moved toward the opening formed by said movable vertical portion of the work support. 70

2. A sewing machine, including in combination a work support, a needle, a driving shaft, a threaded looper, a supporting member for said looper, operative connections between said supporting member and said driving shaft, whereby said supporting member may be moved for causing said looper to cooperate with said needle, a work support having a vertical portion covering said looper, means whereby said vertical portion may be moved to give access to the looper for threading, said operative connections between said looper supporting member and the driving shaft including a yieldingly pressed latch for holding said looper supporting member connected to the driving shaft, whereby upon the release of said latch said looper supporting member may be turned so as to move the looper toward the opening formed by said movable vertical portion of the work support. 85 90 95 100

3. The combination with a needle, means for operating the same, of a looper shaft, a looper secured thereon, mechanism for operating said looper shaft, including a crank frame, loose on said looper shaft with means for operating the same and means for connecting said crank frame to said shaft whereby the looper shaft may be operated by the movements of the crank frame. 105 110

4. The combination with a needle, means for operating the same, of a looper shaft, a looper secured thereon, mechanism for operating said looper shaft, including a crank frame loose on said looper shaft, means for locking the crank frame to the looper shaft, said means including a latch. 115 120

5. The combination with a needle, means for operating the same, of a looper shaft, a looper secured thereon, mechanism for operating said looper shaft, including a turning block rigidly secured to said looper shaft, a crank frame loose on said looper shaft and means for connecting said block and frame. 125

6. The combination with a needle, means for operating the same, of a looper shaft, a looper secured thereon, mechanism for oper- 130

- ating said looper shaft, including a turning block rigidly secured to said looper shaft, a crank frame loose on said looper shaft and a latch for connecting said block and frame.
6. 7. The combination with a needle means for operating the same, of a looper shaft, a looper secured thereon, mechanism for operating said looper shaft, including a turning block rigidly secured to said looper shaft, a 70 crank frame loose on said looper shaft, and a spring-controlled latch for connecting said block and frame; substantially as described.
8. A sewing machine, including in combination, a bed plate, a cloth plate, the front 15 portion of said cloth plate being hinged to the bed plate and having also a vertically extending portion to inclose the operating parts, a thread-carrying looper mounted to oscillate between said bed plate and said 20 cloth plate, means for oscillating the same, and means for disconnecting said looper from its oscillating means, whereby the same may be turned to a position for convenience in threading.
- 25 9. The combination with a work support, of stitch-forming mechanism including a needle, a main shaft located beneath said work support, means for operating said needle from said main shaft, a looper shaft 30 located beneath said work support, a rock lever mounted beneath said work support, means for rocking said lever from said main shaft, and means for oscillating said looper shaft from said rock shaft, including a crank 35 frame loose on the looper shaft, devices for securing said crank frame to said looper shaft, and a link connecting said crank frame to said rock lever.
10. The combination with a work support, 40 of stitch-forming mechanism including a needle, a main shaft located beneath the work support, means for operating said needle from said main shaft, a looper shaft mounted beneath the work support, a looper 45 carried thereby, a rock lever mounted beneath the work support, means for rocking said lever from said main shaft, a crank frame loose on the looper shaft, means for detachably connecting said crank frame to 50 said looper shaft, a link connecting said rock lever and said crank frame, said link and said rock lever forming a toggle, whereby a variable movement is imparted to said looper.
- 55 11. The combination of a looper shaft, a looper connected thereto, said looper having an open sided bearing whereby the same may be detached from said shaft.
- 60 12. In a sewing machine, the combination with a driving shaft, of a looper shaft, means for moving the same longitudinally, and means for oscillating said shaft, including a rocking lever as B, a link connecting the same to the main shaft intermediate the 65 ends of the rocking lever, said rocking lever
- at its upper end being bent back toward the main shaft, a crank frame on the looper shaft, and a link connecting the end of the rocking lever with the crank frame, said link and rocking lever forming in effect a toggle, whereby variable movement is imparted to the looper; substantially as described. 70
13. The combination of a needle, a looper and means for operating the same, of a spreader bar having slotted ends, means for 75 adjustably attaching said bar to the throat plate and a projecting spreading finger carried by said bar.
14. The combination with a plurality of needles and loopers, and means for operating the same, a spreader bar secured to the throat plate and having a series of supporting fingers lying adjacent the needle slots for engaging the thread carried by the looper and positioning the same for the entrance of the needle between said thread and the body of the looper; substantially as described. 80
15. The combination of a feeding mechanism, a needle, a looper, means for moving 90 said looper forward into the needle loop in a line substantially parallel with the line of feed and for withdrawing the looper from the needle loop, means for giving the said looper a lateral movement while in the 95 needle loop and means for engaging the looper thread for separating said looper thread from the body of the looper so as to permit the needle to pass between the looper thread and the body of the looper. 100
16. A combination of a feeding mechanism, of a plurality of needles arranged in a line substantially at right angles to the line of feed, a thread carrying looper co-operating with each needle, means for moving 105 said loopers into and out of their respective needle loops, each looper moving into the needle loop in a direction opposed to the direction of feed and in a line substantially parallel with the line of feed, means for 110 moving the loopers laterally while in the needle loops and a spreader for engaging each looper thread for separating the looper thread from the body of the looper to permit each needle to pass between the looper 115 thread and the body of the looper with which it co-operates.
17. The combination of a feeding mechanism, a needle, a looper, a looper support, means for moving said looper support back and forth in a plane substantially parallel with the line of feed, means for giving said looper a lateral movement at the forward end of its stroke, and a spreader arranged in the path of the looper thread whereby the 120 looper thread engaged by the spreader is separated from the body of the looper for the entrance of the needle between said looper body and the looper thread.
18. The combination of a needle, a looper, 125

a looper support, means for moving said substantially a right line on one side of the needle path and parallel with the line of feed and for retracting said loop in substantially a right line on the other side of the needle path, and for giving said looper an extended dwell at the forward end of its stroke, means for moving said looper laterally during said dwell, and a spreader arm 10 ranged in front of the needle relative to the movement of the looper and in the path of

the looper thread, whereby said looper thread is separated from the body of the looper for the entrance of the needle between said looper and said looper thread. 15

In testimony whereof I affix my signature, in presence of two witnesses.

LANSING ONDERDONK.

JOHN H. HOWELL, Jr.

Copies of this patent may be obtained for five cents each, by addressing the "Commissioner of Patents, Washington, D. C."

It is hereby certified that in Letters Patent No. 1,123,576, granted January 5, 1915, upon the application of Lansing Onderdonk, of New York, N. Y., for an improvement in "Multiple-Needle Chain-Stitch Machines," an error appears in the printed specification requiring correction as follows: Page 5, line 1, after the word "said" insert the words and syllables *loop* *forward* *into* *the* *needle* *loop* *in* *sub-*; and that the said Letters Patent should be read with this correction therein that the same may conform to the record of the case in the Patent Office.

Signed and sealed this 30th day of March, A. D., 1915.

[SEAL.]

J. T. NEWTON,

Acting Commissioner of Patents.
